UNITED STATES PATENT OFFICE.

ALBERTO AZCONA, OF MAGDALENA, MEXICO.

COMBINED RULER AND BLOTTER.

Application filed December 5, 1922. Serial No. 605,089.

To all whom it may concern:

Be it known that I, ALBERTO AZCONA, a citizen of Mexico, and a resident of Magdalena, Sonora, Mexico, have invented a new and Improved Combined Ruler and Blotter, of which the following is a full, clear, and exact description.

This invention relates to an improved article of stationery and has particular reference to a combined blotter and ruler.

One of the principal objects in view resides in the provision of a device of the character set forth which facilitates the ruling of lines with pen and ink without soiling or blotting the paper, and the blotting of lines or writing by rolling the blotter over the same, thus preventing smearing and further eliminating the loss of time in picking up a separate blotter for blotting lines made by the use of an ordinary ruler.

The invention further contemplates the provision of a blotter as a new article of manufacture which consists of a plurality of telescopic sections of blotting material, the outermost sections of which are adapted to be successively removed and discarded when filled with ink to such an extent as to be unfit for further use.

As a further object the invention contemplates a device of the character described which is extremely simple in its construction, inexpensive to manufacture, and which is highly efficient in its use.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

45 In the drawing—

Figure 1 is a perspective view of a combined blotter and ruler constructed in accordance with the invention.

Fig. 2 is a view illustrating the sections 50 in partially telescoped relation.

Referring to the drawing by characters of reference, the combined blotter and ruler comprises a center or core 10 of substantially

circular formation in cross section, which is constructed of a blotting or absorbent material. A plurality of outer cylindrical sections 11 and 12 are telescopically associated with each other and the core 10 to make up a complete article. In use the device is adapted to be employed as a ruler for pen and ink lines in which instance the periphery of the outermost section constitutes a straight edge. After the line is ruled, the device may be rolled over the same to prevent blotting and smearing, thus eliminating the loss of time which ordinarily necessitates the picking up and application of a blotter after the ruler is removed. In ordinary writing with pen and ink, the blotter is rolled over the writing thus minimizing the possibility of smearing or otherwise obliterating the same. As the outermost sections become filled with ink to such an extent as to hinder their proper functioning, they are successively removed and discarded to expose and prevent a clean blotting face. The simplicity of the construction and cheapness with which the same may be produced is thought to be obvious, and this combined with the features of utility and advantage over the ordinary methods employed go to make up an essential and saleable article of manufacture.

I claim:

1. As a new article of manufacture, a combined blotter and ruler consisting of a plurality of telescopic sections of blotting material.

2. As a new article of manufacture, a combined blotter and ruler consisting of a plurality of cylindrical telescopic sections of blotting material.

3. As a new article of manufacture, a combined ruler and blotter consisting of a plurality of telescopically associated sections of blotting material, the outermost sections of which are successively removed and discarded to expose and present a clean blotting surface.

4. As a new article of manufacture, a combined ruler and blotter consisting of a plurality of telescopically associated cylindrical sections of blotting material, the outermost sections of which are successively removed and discarded to expose and present a clean blotting surface.

5. As a new article of manufacture, a combined ruler and blotter consisting of an elongated core of circular formation constructed of blotting material and a plurality of telescopically associated elongated cylindrical sections of blotting material fitted over said core and adapted to be successively

removed and discarded when filled with ink whereby to expose and present a clean blotting surface.

ALBERTO AZCONA.
